United States Patent Office

Des. 222,161
Patented Oct. 5, 1971

222,161

MODEL RACING CAR

Eric Harrison Broadley, Pangborne, near Reading, England, assignor to Lola Cars Limited, Slough, England

Filed Sept. 2, 1970, Ser. No. 24,813

Claims priority, application Great Britain Mar. 9, 1970

Term of patent 7 years

Int. Cl. D21—01

U.S. Cl. D34—15

FIG. 1 is a top plan view of the model racing car showing my new design; and

FIG. 2 is a front elevational view thereof; and

FIG. 3 is a left side elevational view, the right side being a mirror image thereof; and

FIG. 4 is a rear elevational view thereof.

I claim:

The ornamental design for a model racing car, as shown and described.
